FIG. 5

INVENTOR.
EDWARD FLEMING

BY *Shigley & Harvey*

ATTORNEY.

UNITED STATES PATENT OFFICE.

EDWARD FLEMING, OF COLUMBUS, OHIO.

MAIL BOX.

Application filed December 26, 1924. Serial No. 758,214.

To all whom it may concern:

Be it known that I, EDWARD FLEMING, a citizen of the United States of America, residing at Columbus, in the county of Franklin and State of Ohio, have invented certain new and useful Improvements in Mail Boxes, of which the following is a specification.

My present invention relates to improvements in mail boxes and is not only especially designed for house use in mail deliveries to dwellings but will also facilitate delivery of mail by the mail carrier and insure safety of the mail matter after delivery to the box.

The invention contemplates a mail box, preferably located in the front wall of a dwelling, that is accessible from the outside of the building for delivery of mail by the mail carrier and accessible from inside the house at the convenience of the occupants of the dwelling for withdrawal of mail matter from the box.

The mail box housing or receptacle is of the telescopic type and is adjustable to adapt it for use in houses having walls of varying thickness, and the invention consists in this and in certain other novel features of construction and combinations and arrangements of parts as will hereinafter be more fully set forth and claimed.

In the accompanying drawing I have illustrated one complete example of the physical embodiment of my invention, and a slight modification thereof, wherein the parts are combined and arranged, in accordance with the best mode I have thus far devised for the practical application of the principles of my invention.

Figure 1 is a view in front elevation of the mail box.

Figure 2 is a longitudinal, vertical sectional view through the box on line 2-2 of Figure 1 showing also the house wall in section.

Figure 3 is a horizontal sectional view through the box.

Figure 4 is a view in elevation of the mail box looking at the inner end thereof.

Figure 5 is a longitudinal sectional view of a modified form of the mail box.

In utilizing the device of my invention the mail box is placed within the front or other wall of the building occupied as a dwelling,

an opening being provided therefor in the wall 10, which opening extends through the wall from the outside front face to the interior face of the wall where the plaster is indicated at 11.

For adjusting the mail box to use in walls of varying thickness and insuring a neat and workmanlike appearance at both the interior and exterior faces of the wall, the box is made up of two sections 12 and 13, the former telescoping within the latter and provided with screws 14 for selective use with several sets of screw holes 15.

The box as a whole is preferably rectangular and the outer end of the outer section 13 is preferably closed by an integral end piece 16 or one so fastened as to defeat unwarranted removal. At its upper portion this end piece 16 has a mail introducing slot 17 with an inner hinged cover 18 therefor permitting introduction, but preventing removal, of mail. Below the slot 17, end piece 16 has a glass covered sight opening 19, and a paper holding clip 20.

At its inner end, the inner section 12 has a hinged laterally swinging door 21, preferably adapted to be locked in closed position and preferably having a large glass covered sight opening 22, it being intended to exclude all except those authorized to enter and having a key for this purpose.

Within the box is an upwardly opening receptacle 23 having the upper portion of its outer end cut away opposite the mail introducing slot 17 and having an opening 24 in its outer end opposite the sight opening 19. At its inner end the receptacle has a handle 25 by means of which it may be readily removed when the inner door 21 has been opened.

In use, the length of the box is adjusted to the thickness of the wall in which it is to be used and after the proper length is secured the overlapping edges of the box members are secured together by means of the screws 14 and selected screw holes 15 to form a rigid structure.

The free ends of the telescoping sections are fashioned with flanges 26 and 27 which are disposed at an angle to the two sections and form open face plates at the ends of the box. These face plates are larger in dimension than the opening in the wall and therefore close against the wall surfaces around

said opening to prevent draft of air through the wall and give a neat and finished appearance to the structure.

Mail is deposited from the outside of the house or wall through the slot 17 in the outer end 16, and this end, which is provided with the glass panel 19, is also equipped, as before stated, with the spring clip or bracket 20 for the reception of newspapers, magazines and similar mail matter.

When the box is to be installed in old buildings, or where it is not desirable to cut the opening entirely through the wall, as in apartment houses, hallways and the like, a single box section as 28, with a closed interior end may be placed in an opening in the wall as in Figure 5. This box section is provided with flanges 29 forming a face plate and with a door 30 having a mail receiving slot 31, through which the mail is introduced into the receptacle 32 by means of the cut away adjacent end of the latter as in the first form.

While I have described the box as adapted for use in the front wall of a house it will be apparent that the wall structure indi-

cated may be that of a dwelling house, an office, apartment or other place of habitation.

What I claim is:

A mail receiver for extension through a wall opening including two sections in telescoping relation having rigid flanges at their outer ends, means to adjustably connect the telescoping inner portions of said sections whereby to clamp their outer flanges against opposite faces of a wall through which the receptacle is extended, one of said sections having a rigid wall closing its outer end and provided with a mail slot, a door hinged to and normally closing the outer end of the other section, and a mail receptacle in said sections to receive mail through the slot of said rigid wall and restrained by the latter from movement out of the receiver in one direction, said receptacle being freely movable into and out of the receiver through the opposite end thereof with the said door open.

In testimony whereof I have affixed my signature.

EDWARD FLEMING.
